Off-Hanley, Attn.

This technical drawing illustrates a mechanical assembly, likely a conveyor or transport system, shown in two views. The left view, labeled 'Fig. 3', depicts a horizontal assembly with various components labeled with numbers 1 through 18. Components 1, 2, 3, 4, 5, 6, 7, 8, 9, 10, 11, 12, 13, 14, 15, 16, 17, and 18 are visible. The right view, labeled 'Fig. 1', shows a side cross-section of a vertical assembly with components labeled 1 through 11. The drawing uses hatching and cross-hatching to differentiate parts and show assembly details. The inventor's signature, 'Arthur Lipschutz', and the address 'Off-Hanley, Attn.' are handwritten at the bottom right.

UNITED STATES PATENT OFFICE.

ARTHUR LIPSCHUTZ, OF ST. LOUIS, MISSOURI, ASSIGNOR, BY DIRECT AND MESNE ASSIGNMENTS, TO NATIONAL COAL DUMP CAR COMPANY, A CORPORATION OF SOUTH DAKOTA.

COMBINATION FREIGHT AND DUMP CAR.

No. 834,823.

Specification of Letters Patent.

Patented Oct. 30, 1906.

Application filed May 18, 1903. Serial No. 157,694.

To all whom it may concern:

Be it known that I, ARTHUR LIPSCHUTZ, of the city of St. Louis, State of Missouri, have invented a certain new, useful, and Improved 5 Combination Freight and Dump Car, of which the following is a specification.

My invention relates to railroad-cars, and has particular reference to freight-cars that are adapted for the transportation of either 10 bulk, piece, or package freight and are also adapted for employment as dump-cars for carrying and distributing materials, such as sand, gravel, coal, coke, and the like.

The object of my invention is to improve 15 the construction, increase the capacity and strength, and lessen the weight of dump-cars and to provide a car which shall be capable of the uses of an ordinary freight-car in addition to possessing the utility of 20 the most modern dump-cars.

The primary object of my invention is to provide a car that shall be practically self-cleaning and which shall have a level flat bottom when all of its doors are in their 25 normal positions, so that the car will accommodate any sort of freight, being unobstructed by ridges, depressions, or hoppers.

Another object of the invention is to provide a dump-car which shall have a uniform 30 cross-section from end to end with a view to avoiding any diminution of load capacity as compared with ordinary solid-bottom gondola or freight cars.

Another object of the invention is to provide 35 a combination freight and dump car that may take the form of a flat-car, a coal-car, a coke-car, or a box-car without modification or alteration in its underframing or floor.

Another object of the invention is to provide 40 a car of the class described which though having a bottom or floor substantially all of which is arranged to be dropped down shall be of great strength to carry a maximum 45 load and withstand the heavy bumping and pulling strains to which such cars are subjected.

Another object of the invention is to provide 50 a dump-car that may be safely traversed by the trainmen or workmen when the drop-doors are open.

A particular object of the invention is to provide a combination-car which shall have

an all-steel underframe and a superstructure having a steel base, but otherwise preferably 55 composed of wood.

Another particular object of the invention is to provide a combined freight and dump car having a level floor and in which the weight of the load shall be principally sus- 60 tained by the center sill, which rests upon the bolsters or transoms.

Another object of the invention is to provide a car that shall be constructed of plates and shapes obtainable in the open market 65 and to avoid the employment of special shapes and pressed forms.

Another object of the invention is to provide a car of the class described which shall be free from external projections upon its 70 sides, a distinct purpose also being to provide a car of maximum inside width.

My invention consists generally in a combined freight and dump car body comprising the bolsters or transoms in combination with 75 a center sill framed with said bolsters and having a wide flat top, suitable cross-beams, including end beams, suitable side sills, and a plurality of doors occupying the spaces between the several beams and sills. 80

My invention also consists of special novel constructions and combinations of parts, all as hereinafter described, and particularly pointed out in the claims.

The invention will be more readily understood by reference to the accompanying drawings, forming a part of this specification, and in which—

Figure 1 is a side elevation of a combined freight and dump car embodying my invention. Fig. 2 is a plan view thereof. Fig. 3 is a longitudinal vertical section substantially on the line $x-x$ of Fig. 2. Fig. 4 is an enlarged end view of the car. Fig. 5 is a similarly-enlarged vertical cross-section substantially on the irregular line $y-y$ of Fig. 2 corresponding to the planes of the lines $y-y$ of Fig. 1. Fig. 6 is a similar view on the line $z-z$ of Fig. 2 with the drop-doors removed. Fig. 7 is an enlarged vertical sectional detail on the line $u-u$ of Fig. 2. Fig. 8 is a sectional view on the line of $v-v$ of Fig. 7. Fig. 9 is a plan view of the parts shown in Figs. 7 and 8; and Figs. 10 and 11 are respectively a vertical section and a side view of a portion of, 105 the car, showing a modification of the ver-

tical strengthening members or stakes and of the side sill or girder.

The advantages which I seek in a car of the class mentioned are substantially these: 5 First, a perfectly level floor—that is, a floor without obstructions or depressions; second, vertical sides and ends that may be reduced or increased in height according to the use to which the car is to be put; third, a car-body 10 of the same length as the underframe, whereby loss of load capacity is avoided as compared with those cars in which the car-body is located between the ends of the underframe, starting at a considerable distance 15 from said ends; fourth, drop-doors by which substantially the entire load of the car can be dumped without shoveling; fifth, doors of great size that will permit the passage of 20 large rocks or chunks of ore or coal; sixth, few convertible parts, none, if possible, aside 25 from the doors which constitute the floor; seventh, adaptability for use as flat, coal, coke, or box car without reference to the character of the car-floor; eighth, simple and 30 strong floor construction having drop parts which at all times normally enter into the floor structure—that is, parts which are at no time extra or superfluous members, their functions being constant without reference 35 to the character of the load; ninth, strength to withstand heavy bumping and pulling strains in addition to great carrying strength; tenth, freedom from danger to train hands or workmen, who are frequently injured while 40 attempting to traverse cars having the ordinary irregular bottoms; eleventh, lightness and consequent reduction of the dead-weight to be hauled; twelfth, freedom from external irregularities or projections that are dangerous in themselves and tend to increase the 45 damage done in case of a wreck, and, finally, great simplicity and economy of construction.

While other combination-cars may and 45 have possessed one or more of the features and functions above enumerated, each contains objectionable features, such as elevated or inclined ends or floor-ridges or a reduced body or permanent level-floor parts or convertible tilting-floor parts, all of which either 50 reduce the load capacity of the car or restrict the load to certain materials, reducing the earning capacity of the car as a unit or largely increasing the cost of constructing and maintaining the car. The ordinary combination 55 freight and dump cars are also objectionable by reason of their great weight. I conceive that the greatest number of desirable features and advantages attainable in a single 60 car may be secured through simplification of car construction rather than by the addition of unique unusual structures or convertible movable members. My invention proceeds upon this conception, and the gist of the in-

vention resides in the combination of suitable bolsters or transoms with a wide flat-topped center sill, suitable cross beams or sills parallel with said bolsters, suitable side sills or girders which, in effect, are load-inclosing parts only, and two sets of drop-doors, 65 each extending from end to end of the car and said doors being normally in the plane of the top of said center sill. The invention proceeds further and includes novel side members composed of rolled shapes that are 70 made to serve as the base of the car-body superstructure and help retain the load. 75

The main carrying members of this car are the bolsters or transoms and the heavy center sill, and these are essential elements of 80 the novel underframe. Together they support the load between and over the trucks.

In the drawings I have shown only half of the car, same being sufficient for a clear understanding of the invention. There are 85 two bolsters or transoms, one over each truck 2 and each of which comprises two deep transom-plates 2', truss-shaped and joined on the bottom by the angle-bars 2² and the curved bottom plate 2³. At the tops of the 90 transom-plates 2' are the straight angle-bars 2⁴, and said tops are finally joined by the transverse floor-plate 3, which will be more fully described hereinafter. The inner side of the bolster is provided with an intermediate gusset-plate 4 to receive the end of the center sill 5. The center sill is preferably formed in three sections, the long middle section between the two bolsters and the two splices, which extend between the bolsters and the end plates or sills 6 of the underframe. The center sill may, if desired, be spliced through the bolsters; but I find that the construction shown affords greater 95 strength. The center sill 5 is made up of the 100 widely-separated parallel plates 5', which are preferably truss-shaped and joined by the wide bottom plate 5² and the wide top or floor plate 7, suitable angle-bars 5³ and 5⁴ being interposed between the vertical and the horizontal plates. The end of the center sill 105 is spliced to the inner side of the bolster by heavy angles or plates 5⁵, and 5⁶ represents the splice end of the center sill, composed of parallel plates or beams and preferably reinforced by the box-girder 5⁷, which latter is 110 arranged to contain the draft-rigging. Suitable splice-plates join the ends of the parts 5⁶ and 5⁷ to the forward side of the bolster and the end plate or sill of the car. It will be 115 noted that the top or floor plate 7 of the center sill extends from end to end of the car across the bolsters, tying the spliced parts firmly together. To accommodate this arrangement of the center-sill floor-plate, the 120 floor-plate 3 of the bolster is arched or formed over the plate 7, as shown in Figs. 2 and 3, (see 3'). The bolster is thus given great 125

strength in its upper chord without sacrificing the continuous longitudinal floor-plate.

The structure thus far described carries the whole load of the car and with a few parts which are necessary to support and prevent the flexing of the car-floor between the bolsters constitute a rigid underframe. The parts referred to are two or more auxiliary or bracket beams 8, to which I preferably add a number of light fillers or auxiliary cross-beams 9 and the superstructure base members 10, which latter are the only parts in my car that correspond in position to the ordinary side sills or girders and which serve a different purpose. Each cross-beam 8 is made in two parts or brackets, as shown in Figs. 5 and 6. The inner ends of these brackets are practically of the same depth as the center sill, and each bracket comprises the triangular plate 8', supplemented by the angle-bars 8², extending around the edge of the plate upon opposite sides. The butts of the brackets are riveted to the sides of the center sill. The tops of the brackets are preferably flush with the under surface of the longitudinal floor-plate 7 and are covered by short transverse floor-plates 11, the inner ends of which abut against the edges of the floor-plate 7. The brackets are preferably strengthened by the upright intermediate angle-bars 8³, and, if desired, the cross-beam as a whole may be strengthened by the employment of one or more diaphragms or fillers within the center sill, as indicated in Figs. 5 and 6. 12 12 represent the edge floor-plates. These are laid upon the ends of the bracket-beams, the bolsters, and the end sills and are there secured. They extend the full length of the underframe and are supported by the narrow end or platform plates 12'. These plates form the outside chords of the frame. The superstructure base members 10 are wide shallow channel-beams. The flanges of these beams preferably extend outwardly, the bottoms of the channels forming the smooth inner side walls of the car-body. The channels or beams 10 may be comparatively light. They rest upon the large plates 12 and are supported by the bracket-beams and the bolsters and are subjected to little more than the lateral stress of the load that may be contained in the car-body. The proportions of the parts are such that the bracket-beams 8 serve to and are intended to support the lateral load on each side of the center sill between the main bolsters or transoms. The base members or beams 10 are preferably of less length than the underframe, being coextensive with the car-body, which is shorter than the underframe to the extent to which the ends of the car-body are set back of the end sills. The channel-beam superstructure-base for the body is preferably extended around the ends

of the car, as shown by the short channel-beam 10' in Figs. 1, 3, and 4. These end beams 10' rest upon the end plates 12', that correspond to the edge plates 12. A perfectly stable and rigid base for the superstructure upon the underframe is thus obtained and effectively strengthens the superstructure against horizontal lateral blows and strains, particularly those directed from the interior of the car, as at times when the car is being loaded with heavy rocks or chunks of ore. The car-body above the channel-beam base may be of any desired construction and material; but I prefer to make it of wood, using heavy planks 13, the lower ones of which rest upon the upper flanges of the channel beams or sills 10, which make a good foundation therefor. The security of this foundation and the stability of the lower corners of the car-body afforded by the metallic construction enable me to dispense with many of the upright strengthening bars or stakes that are usually employed. These stakes 14 are arranged at convenient intervals, preferably at the ends of the bolsters and the cross-beams, and comprise wooden or angle or channel bars, the lower ends of which extend to the floor-line—to wit., the tops of the floor-plates—and are secured, preferably, to the inner sides of the channel-beams 10, the connections being supplemented by suitable angle or gusset plates 14'. The side and end planks 13 are bolted or riveted to the stakes, and the corners of the car-body are finished by corner-plates 13', applied to the outside and, if desired, the inside also. The structure may be modified, as illustrated in Figs. 10 and 11, wherein the stakes are applied to the outside of the car, being riveted to the channels 10, which are here reversed. In this case I sometimes prefer to extend the ends of the stakes down across the ends of the bolsters and cross-beams, making the connections by means of the angle-plates 14². I do not advocate this construction, as I prefer the arrangement of the stakes within the car-body, so as to leave the exterior free from ribs or projections, which are always an element of danger.

It will be observed that large spaces are left between the end sills and the bolsters and between the bolsters and cross or bracket beams. These spaces are occupied by the drop-doors, which may be of either wooden or metallic construction. The doors are of the same width throughout the car, and I preferably use only two doors 15 15 between the bolster and the end sill, one on each side of the center sill. It would be possible to use a single door between the bolster and the adjacent bracket-beam; but in most cases a single door of this length would prove inconvenient in this position or between adjacent

bracket-beams at the middle of the car. I therefore divide each such space into two or more parts by one or more of the short cross-beams or fillers 9, that extend from the center sill to the side beams 10, having their outer ends secured to the edge plates and the lower flanges to the beams 10. The intermediate doors are thus made of about the same length as the end doors and may be identical therewith, so that the load areas of the doors will be the same throughout the car. The floor-plates 11' of the auxiliary or filler beams named are wider than the tops of said beams, as in the case of the bracket-beams. (See Figs. 1 and 2 and the detail Figs. 7, 8, and 9.) These transverse floor-plates 11 11', each overhanging its beam, correspond to the overhanging edges of the center sill, with its floor-plate 7 and the edge and end plates 12 and 12'. The doors 15, whether made of metal plates or of wooden planks, as shown, are flanged or rabbeted to receive these overhanging edges of the sills and beams, so that the tops of the doors may be flush or in the same plane with the floor-plates 7, 12, 12', 11, and 11'. The joints formed are tight and all danger of car leakage is avoided. The doors may be hinged between the outer ends of the several transverse parts or beams when it is desired to adapt the car for center-ballasting purposes; but in most cases I prefer to hinge the doors upon the center sill, as illustrated, using simple hinge parts 15', that are preferably attached to the horizontal flanges of the angle-bars 15², which I use to strengthen and form a frame for the planks making up each door. The hinge attachments may be made to the side plates of the center sill or to the lateral portions of the cross-beams, as may prove most convenient; but in every case the hinge is preferably set well back under the overhanging top flange of the center sill. The outer edges of the door are preferably provided with the depending lugs 15³, to which the drop or supporting chains 16 are attached. These chains are wound on the winding-shafts 17, that have bearings in the ends of the several cross-beams and the bolsters. The shafts are most conveniently accommodated directly beneath the large plates 12 and are protected thereby. The winding and locking devices 18 are arranged on the end sills of the underframe and may be of any suitable construction. By means of the same the shafts may be locked to hold the doors in their raised normal positions or unlocked to permit the doors to fall and discharge the contents of the car. The devices 18 are also adapted for rotating the shafts to wind up the chains and raise the doors. The arrangement of the winding-shafts within the vertical planes of the car sides is particularly advantageous, as the winding-shafts and chains are thus removed from the usual ex-

posed positions on the sides of the car and no longer form dangerous side projections.

When the doors of the car are in their normal positions, the car is very similar to an ordinary flat-bottomed gondola car and has all the advantages of such a car, including the particular feature of a solid and perfectly level floor with straight sides and ends, giving the car full capacity for any kind of freight. As a dump-car it possesses the important characteristic of being self-cleaning. The small quantity of material that will finally lodge upon the wide center sill may be disregarded in this connection. The center sill when cleared is wide enough to serve as a runway or walk, and the trainmen and workmen may therefore traverse the car with safety, whether or not the doors are in their raised positions. The wide center sill also makes the car capable of withstanding the heaviest of bumping or pulling strains.

An essential and novel feature of my invention is the center sill that is of the same width from end to end, permitting the employment of doors of uniform width.

As it is obvious that numerous modifications of my invention will readily suggest themselves to one skilled in the art, I do not confine the same to the specified constructions herein shown and described.

Having thus described my invention, I claim as new and desire to secure by Letters Patent—

1. A dumping-car underframe, provided with a center sill, and with bolsters or transoms arranged between the ends of said sill, in combination with a floor-plate extending from end to end of said sill, and transverse floor-plates covering said bolsters or transoms and extending across the center-sill floor-plate, substantially as described.

2. In a dumping-car underframe, the center sill, in combination, with the bolsters or transoms, framed with said sill at intermediate points thereon, a continuous floor sheet or plate provided on the top of said center sill and of substantially the same length, and continuous floor-plates for said bolsters, overlying the center-sill floor-plate, substantially as described.

3. A car of the class described, having an underframe comprising the bolsters or transoms, in combination, with a wide, center sill to withstand the buffing or bumping and pulling strains and sustain the load, two or more bracket-beams extending from the intermediate portions of said center sill, suitable edge floor-plates or floor-sections, and doors filling the spaces between such parts, substantially as described.

4. In a car-underframe, the bolsters or transoms, in combination with the center sill, composed of parallel members bound by plates in horizontal planes, the bracket-

beams supported by said center sill between said bolsters, the end sills, the base members supported by said bolsters, bracket-beams and end sills and the floor arranged on said sills and beams, substantially as described.

5. In a car-underframe, the bolsters or transoms, in combination with the center sill, composed of parallel members bound by plates in horizontal planes, the bracket-beams supported by said center sill between said bolsters, the end sills, the base members supported by said bolsters, bracket-beams and end sills and the drop-doors normally in the plane of the top of said center sill, substantially as described.

10. In a car-underframe, the bolsters or transoms, in combination with the center sill, composed of parallel members bound by plates in horizontal planes, the bracket-beams supported by said center sill between said bolsters, the end sills, the base members supported by said bolsters, bracket-beams and end sills and the drop-doors arranged in two sets, one on each side of said center sill, 25 and each said set extending from end sill to end sill of the car.

15. In a freight and dump car, the center sill, in combination with the bolsters, the intermediate bracket-beams extending from said center sill, the car sides supported by said bolsters and bracket-beams, the drop-doors and the winding-shafts journaled on the ends of said bolsters and beams, for supporting the free ends of said doors, substantially as described.

20. In a combined freight and dump car, the combination of the center sill with the several transverse elements extending therefrom, said sill and said elements having floor-plates in substantially the same plane, the hinged doors between said elements, having their tops in the plane of said plates, and the edge floor-plates arranged upon the ends of said transverse elements, substantially as described.

25. In a combined freight and dump car, the combination of the center sill with the several transverse elements extending therefrom, said sill and said elements having floor-plates in substantially the same plane, the hinged doors between said elements, having their tops in the plane of said plates and the edge floor-plates arranged upon the ends of said transverse elements, the edges of said floor-plates overhanging the edges of said doors and making tight joints therewith, substantially as described.

30. In a combined freight and dump car, a suitable underframe provided with door-openings, in combination with the flanged beams or base members, resting upon said underframe and a superstructure whereof said members constitute the base, substantially as described.

35. In a combined freight and dump car, a suitable underframe provided with door-openings, in combination with the flanged beams or base members, resting upon said underframe, a superstructure whereof said members constitute the base, and suitable stakes forming a part of the superstructure and having their lower ends fastened upon said members, substantially as described.

40. In a freight-car, the bolsters, in combination with the flanged base members, resting upon the tops of said bolsters and having vertical webs, the car sides erected on said base members and a suitable car-floor, substantially as described.

45. In a combined freight and dump car, the center beam, in combination with the bolsters extending therefrom, suitable auxiliary transverse beams or members, the floor-plates, including the edge floor-plates 12 and 12', framing the openings of the underframe thus formed and a plurality of hinged doors normally closing said openings, substantially as described.

50. In a combined freight and dump car, the center beam, in combination with the bolsters extending therefrom, suitable auxiliary transverse beams or members, the floor-plates, including the edge floor-plates 12 and 12', framing the openings of the underframe thus formed, a plurality of hinged doors normally closing said openings and the superstructure base, comprising flanged girders, having their lower flanges secured upon said edge floor-plates, substantially as described.

55. In a dumping-car, the combination of the transverse members of the underframe and the drop-doors arranged between the same, with the edge floor-plates arranged upon the ends of said members, and the door-operating mechanisms in the ends of said elements, beneath said floor-plates, substantially as described.

60. In a dumping-car, the combination of a center sill, with the transverse elements extending therefrom, the doors arranged between said elements, the side members arranged upon said elements at the ends thereof and the door-operating mechanisms in the ends of said elements, beneath said side members, substantially as described.

65. In a combined freight and dump car, the bolsters, in combination with the center sill, the intermediate or bracket beams extending from said center sill, the auxiliary beams or fillers 9, the flanged-beam base members 10, resting upon said bolsters and bracket-beams and whereto the outer ends of said fillers are secured, the drop-doors, and the hinge and operating-supports therefor, adjacent to said center sill and said base members, substantially as described.

70. In a combined freight and dumping car, a suitable underframe provided with a

- plurality of door-openings, in combination with doors normally filling said openings and hinged at their inner edges, each of said doors extending from the center sill of the under-frame to the side sill thereof, the car sides resting upon said underframe, and door-operating shafts arranged beneath said sides and connected with said doors, substantially as described.
19. In a combined freight and dumping car, a center sill, in combination with transverse elements, car sides arranged on the underframe thus formed, a plurality of drop-doors filling the openings in said underframe and hinged adjacent to said center sill, and fastenings for the free ends of said doors, beneath the car sides, each said door extending from said center sill to a car side, substantially as described.
20. In a combined freight and dumping car, a suitable center sill, provided with a floor-plate, in combination with transverse elements including the bolsters, framed with said center sill, the flanged beams having vertical webs and forming the car sides, floor-plates beneath said beams, and a plurality of doors having their edges underlying said floor-plates, substantially as described.
21. A combined freight and dump car body, comprising suitable bolsters, in combination with the center sill, framed with said bolsters and having a wide, flat top, suitable cross-beams including end sills, suitable base members resting upon said beams, and a plurality of doors occupying the spaces between the sills, beams and base members and extending to the car sides, substantially as described.
22. A dumping-car underframe, having a center sill framed with the center sill at intermediate points thereof, bolsters and end sills, in combination with a continuous floor-plate, arched over the center sill, extending from end to end of the bolster, and riveted to it, substantially as described.
23. In a dump-car, the center sill, in combination with the bolsters, less in height on the outside than on the inner end, the intermediate bracket-beams extending from said center sill and the flanged girders projecting over said bracket-beams with their whole height, having vertical webs and resting upon said bolsters and bracket-beams, substantially as described.
24. In a dumping - car underframe, the bolsters, in combination with a center sill, intermediate bracket-beams extending from said center sill, suitable end sills, the car sides resting upon the ends of said bolsters and bracket - beams, said car sides being principally supported from the center sill through the medium of said bracket-beams, and two sets of drop-doors filling the openings between the center sill and said car sides; said center sill being capable of sus-
- 70 taining the maximum car-load, whereby the car sides are substantially relieved from strains.
25. In a dumping-car, an underframe comprising bolsters, in combination with a wide-topped center sill, intermediate bracket-beams extending from said center sill, the car sides having their intermediate portions supported by said beams, sets of drop-doors on opposite sides of said center sill and substantially in the plane of the top thereof, means for supporting the free ends of said doors and means closing the door-joints, the arrangement being such that the car-load is substantially wholly sustained by said center sill and said bolsters, substantially as described.
26. In a combined freight and dump car, a center sill, in combination with the bracket-beams and bolsters extending therefrom, said center sill having a wide, flat top forming a runway, as described, drop-doors, hinged adjacent to said center sill, and normally in the plane of the top thereof, and parts resting upon the ends of said bolsters and bracket-beams and lapping over the free edges of said doors, substantially as described.
27. In a combined freight and dump car, a center sill, in combination with the bracket-beams and bolsters extending therefrom, said center sill having a wide, flat top forming a runway as described, drop-doors, hinged adjacent to said center sill, and normally in the plane of the top thereof, parts resting upon the ends of said bolsters and bracket-beams and lapping over the free edges of said doors, and suitable means underlying said doors for operating and supporting them, substantially as described.
28. In a combined freight and dump car, an underframe comprising a wide-topped box-girder-like center sill, in combination with bolsters, bracket-beams and fillers, extending from said center sill, car sides supported upon the ends of said bolsters, bracket-beams and fillers and a plurality of drop-doors hinged adjacent to said center sill, normally closing the openings of the underframe and completing the floor thereof, substantially as described.
29. In a dumping - car underframe, the bolsters and the intermediate bracket-beams, in combination with a wide box-girder-like center sill capable of and for sustaining the maximum car-load, car sides and ends supported by said center sill through the medium of said bolsters and bracket-beams, and a plurality of drop-doors each extending from said center sill to said car sides, substantially as described.
30. In a combined freight and dump car, the center sill, in combination with bolsters framed therewith, one or more bracket-beams extending from each side of said center sill, transverse fillers arranged between

said bolsters and bracket-beams and framed to said center sill, side girders supported by said bolsters and bracket-beams and in turn supporting the outer ends of said fillers and a 5 plurality of drop-doors normally filling the openings between such parts, substantially as described.

31. In a dumping-car underframe, a center sill, in combination with end sills, bolsters, cross-beams, a continuous flat floor-sheet overlying said center sill, continuous edge floor sheets or plates parallel with the center floor-sheet and secured upon said end sills, bolsters and cross-beams, and suitable 10 transverse flat floor-sheets upon said end sills, bolsters and cross-beams, substantially as described.

32. In a dumping-car underframe, a center sill, in combination with end sills, bolsters, cross-beams, a flat floor-sheet overlying said center sill, edge floor sheets or plates parallel with the center floor-sheet and secured upon said end sills, bolsters and cross-beams, suitable transverse flat floor-sheets upon said end sills, bolsters, cross-beams, and doors hinged within the underframe with their edges underlying said floor-sheets, substantially as described.

33. In a dumping-car underframe, a center sill, in combination with end sills, bolsters, cross-beams, a continuous flat floor-sheet overlying said center sill, continuous edge floor sheets or plates parallel with the center floor-sheet and secured upon said end sills, bolsters and cross-beams, suitable transverse flat floor-sheets upon said end sills, bolsters, cross-beams, and doors hinged within the underframe with their edges underlying said floor-sheets, substantially as described.

34. In a combined freight and dump car, a center sill, in combination with bolsters, suitable cross-beams, a superstructure base comprising upright channel members resting upon said bolsters, two sets of drop-doors extending from end sill to end sill, on opposite sides of said center sill, each said door extending from said center sill to said channel members, and means for operating said doors, substantially as described.

35. In a combined freight and dump car, a center sill, in combination with bolsters, suitable cross-beams, a superstructure base comprising upright flanged beams resting upon said bolsters, two sets of drop-doors 55 extending from end sill to end sill, on opposite sides of said center sill, each said door extending from said center sill to a flanged

beam, suitable stakes secured to said flanged beams, and wooden planks resting upon said flanged beams and secured to said stakes, 60 substantially as described.

36. In a dumping-car, a center sill, in combination with bolsters, intermediate bracket-beams, end sills, car sides supported by said bolsters and bracket-beams, drop-doors forming the car-floor, and winding-shafts journaled in said bolsters, beams and end sills, for operating said drop-doors, substantially as described.

37. In a combined freight and dumping car, car sides, in combination, with an underframe, a flat level car-floor upon the top of said underframe, said floor being substantially entirely composed of drop-doors, door-hinges adjacent to the center sill of the underframe, and door-operating shafts supported by the said underframe adjacent to said car sides, substantially as described.

38. A combined freight and dump car having a level floor substantially wholly composed of drop-doors, a center-sill structure whereto said doors are hinged, car sides, and means beneath the level of the closed doors and beneath said car sides for operating said doors, substantially as described.

39. In a combined freight or dump car, the transverse members of an underframe, in combination with car sides arranged thereon, edge floor-plates, floor-forming drop-doors hinged at their inner ends, depending outwardly - extending lugs upon said doors adapted to close beneath said edge floor-plates, winding-shafts arranged beneath said edge floor-plates, and means connecting said shafts and lugs, substantially as described.

40. In a combined freight and dump car, an underframe provided with a plurality of door-openings, in combination with car sides, two series of doors hinged adjacent the sides of the center sill of the car and forming substantially an entire level car-floor, downwardly and outwardly extending lugs upon the free ends of said doors, and door-operating shafts provided in said underframe and connected with said lugs for raising and lowering said doors, substantially as described.

In testimony whereof I have hereunto set my hand, this 2d day of May, 1903, at St. Louis, Missouri, in the presence of two witnesses.

ARTHUR LIPSCHUTZ.
